UNITED STATES PATENT OFFICE.

CHARLES KONRAD BRANDSTROM, OF SEATTLE, WASHINGTON.

TROWEL.

1,111,433.

Specification of Letters Patent. Patented Sept. 22, 1914.

Application filed February 11, 1914. Serial No. 818,143.

To all whom it may concern:

Be it known that I, CHARLES KONRAD BRANDSTROM, citizen of the United States, residing at Seattle, in the county of King and State of Washington, have invented certain new and useful Improvements in Trowels, of which the following is a specification, reference being had to the accompanying drawings.

10 This invention relates to new and useful improvements in trowels and more particularly to a sanitary cove plaster and cement trowel, the main object of the invention being to provide a trowel of this character 15 wherein means is provided so that the same may be used upon perpendicular and horizontal surfaces and also upon concave and convex surfaces.

Another object of the invention is the 20 provision of a trowel of the above character which will possess advantages in points of efficiency and durability, is inexpensive to manufacture and at the same time is simple in construction and operation.

25 With the above and other objects in view as will become apparent as the description proceeds, the invention consists in certain constructions, combinations and arrangements of the parts that I shall hereinafter 30 fully describe and claim.

For a full understanding of the invention, reference is to be had to the following description and accompanying drawings, in which—

35 Figure 1 is a top plan view of a trowel constructed in accordance with my invention, Fig. 2 is a side elevation, Fig. 3 is a transverse sectional view taken on the line 3—3 of Fig. 1, Fig. 4 is a detailed enlarged 40 sectional view illustrating the manner of attaching the reinforcing rib to the blade, Fig. 5 is a detail perspective view of the screwing bolt, Fig. 6 is a detail perspective view of the pivoted catch member, Fig. 7 is a 45 detail perspective view of the operating lever and Fig. 8 is a side elevation illustrating a slightly modified form of the device.

In carrying out my invention, the blade 1 is formed of spring steel or other similar 50 material and centrally arranged thereon at one end is a stationary ridge 2, which is riveted or otherwise secured to the blade 1. Projecting upwardly from the inner end of the ridge 2 is the standard 3, the upper end 55 of which is circular in form and provided with a threaded opening 4. The handle

member 5 is secured to the upper end of the standard 3 by means of the longitudinal bolt 6 which extends through the handle 5 and the threaded end thereof engages with 60 in the opening 4 so that when the bolt is securely tightened, the handle 5 will be fastened in its effective position.

In order to reinforce and stiffen the resilient blade 1, I provide a detachable rib 7, 65 which is preferably formed of steel and tapered toward one end as indicated at 8 while the other end thereof is hollow and preferably semi-circular in cross section as indicated at 9. The tapering end 8 is adapted 70 to be removably engaged beneath a keeper 10, the ends of which are riveted or otherwise secured to the blade 1 as shown at 11, extending within the inner end of the rib 7 is the inner end of the ridge 2, 75 which is provided with an inwardly projecting flange 13 and in order to securely fasten the rib 7 in position, a movable bolt 14 is provided having a catch 15 which is adapted 80 to engage the flange 13, to securely retain 85 the inner end of the rib 7 in position. This bolt 14 is actuated by means of a lever 16 one end of which is mounted upon the upper end of the bolt while the other end thereof is provided with an upwardly projecting handle portion 17 adapted to be 90 readily grasped by the fingers to rotate the bolt 14 and engage or disengage the catch 15 with the flange 13. The inner end of the rod 7 is further retained in position by 95 a pivoted catch 18 having an arcuate lower end 19 adapted to engage with the upper surface of the semi-circular portion 9 of the rib 7. The catch 18 is pivotally mounted upon a movable lever 20, said lever being pivotally mounted upon the standard 3 and provided at its lower end with a handle member 21 whereby the lever may be 100 readily actuated when desired. The lever 20 is provided in its body portion with two spaced openings, one of said openings being adapted to receive the pivot pin which secures said lever to the standard 3, the other of said openings being adapted to receive the pivot pin which fastens the catch member 18 to the lever. Thus as the lever 20 is actuated, the catch member 18 will be 105 engaged and disengaged from the upper surface of the rib 7. As illustrated in Fig. 3, the catch member 18 is in its effective position, the handle 21 of the lever being arranged in lowered position and as the lower 110

end thereof is slightly curved, the finger may be readily inserted beneath the same to release the catch 18 when it is desired to remove the rib 7. In removing the rib 7, 5 the catch 18 is first released and the bolt 14 is then disengaged from the flange 13 so that the rib may be readily removed from the blade 1.

It will be apparent from the foregoing 10 that any number of the ribs 7 may be used and will be of different radius, and either elliptical or circular in shape to provide a universal trowel.

While I have shown and described the rib 15 7 as a perfectly straight rigid rib, it will be apparent that in using my improved trowel, on cove work, it will be necessary to provide a rod having a curved outer end as illustrated in Fig. 8. The curved rod illustrated in Fig. 8, is secured to the blade 1 by first bending upwardly upon the blade so that the tapering end 8 of the rib may be engaged beneath the keeper 10. The inner end of the rod is then secured in position 20 and retained by means of the pivoted catch 18. It will be apparent that the straight rib in Fig. 2, may be readily removed and a curved rod as illustrated in Fig. 8, placed in its operative position.

30 The handle member 5 while shown in the drawings as disposed upon one end of the trowel, may be readily changed to the opposite side of the standard 3 and used equally as well.

35 My improved trowel is extremely simple in construction and can be manufactured at comparatively low cost.

While I have shown and described the preferred form of my invention, it will be 40 obvious that various changes in the details of construction and in the proportions may be resorted to for successfully carrying my

invention into practice without sacrificing any of the novel features or departing from the scope of the appended claims.

45

Having thus described the invention, what is claimed is:

1. A trowel of the class described including a resilient blade, a ridge secured thereto, a standard extending outwardly from the ridge, a stationary rib having a tapering end, a keeper adapted to receive said tapering end and means for removably securing the other end of the rib to the blade.

55

2. A device of the class described including a resilient blade, a ridge plate secured thereto, a standard projecting outwardly from said plate, a keeper carried by one end of the blade, a stationary rib having one end removably engaged beneath said keeper, the other end of said rib being hollow and substantially semi-circular in form, a flange formed on the inner end of the ridge plate, a movable bolt carried by said rib having a catch adapted to engage said flange and means for actuating said bolt to engage and disengage the catch.

60

3. A device of the class described including a resilient blade, a ridge secured thereto, an outwardly projecting standard formed on said ridge, a reinforcing rib, a keeper secured to one end of the blade and adapted to receive one end of the rib, a pivoted lever mounted upon said standard and a pivoted catch member carried by said lever and adapted to engage the inner end of said rib and retain the same in position upon the blade.

65

70 In testimony whereof I hereunto affix my signature in the presence of two witnesses. 80
CHARLES KONRAD BRANDSTROM.

Witnesses:

ROBERT WAKELIN,
CLARENCE P. SEELEY.
